UNITED STATES PATENT OFFICE.

GEORGE D. HOFFMAN, OF CHICAGO, ILLINOIS, ASSIGNOR TO NORWALD MANUFACTURING COMPANY, OF CHICAGO, ILLINOIS.

RADIATOR-VALVE.

1,087,119.

Specification of Letters Patent. Patented Feb. 17, 1914.

Application filed November 7, 1910. Serial No. 591,098.

To all whom it may concern:

Be it known that I, GEORGE D. HOFFMAN, a citizen of the United States, residing at Chicago, county of Cook, State of Illinois, have invented a certain new and useful Improvement in Radiator-Valves, and declare the following to be a full, clear, and exact description of the same, such as will enable others skilled in the art to which it pertains to make and use the same, reference being had to the accompanying drawings, which form a part of this specification.

My invention has for its object to provide a novel and efficient valve for permitting the escape of air or of air and water from radiators, preventing the escape of steam, and maintaining a partial vacuum in the radiators when steam is shut off.

The various features of novelty whereby my invention is characterized will herein-after be pointed out with particularity in the claims; but for a full understanding of my invention and of its objects and advantages, reference may be had to the following detailed description taken in connection with the accompanying drawing, wherein:

Figure 1 is a side elevation of a preferred form of valve; Fig. 2 is a central vertical section on an enlarged scale; and Fig. 3 is an elevation of the strainer on the same scale as Fig. 1.

Referring to the drawing, A represents a casing, illustrated as cylindrical, having one end closed by a wall A'.

B is a cap screw-threaded or otherwise detachably secured upon the open end of the casing for the purpose of closing the same.

C is a nipple secured in an opening in the side of the casing and adapted to connect the interior of the casing with the interior of a radiator.

D is a cage or auxiliary casing, open at the ends and somewhat smaller in diameter than the main casing.

E is a gasket arranged between the lower edge of the member D and the bottom wall of the casing for the purpose of making tight joint. A similar gasket F lies between the upper edge of the member D and the underside of the cap. The member D may conveniently be centered within the outer casing by means of an annular flange a projecting inwardly around the top of the main casing and leaving a central opening just

large enough to receive the member D. The gasket F preferably lies upon the flange a, projecting inwardly beyond the same so as to engage the member D. In this way the gasket serves the double purpose of making tight joints between the main casing and its cap and between the member D and the cap.

The member D is preferably made of sheet metal or in the form of a thin casting having a plurality of windows d. Each of the windows is covered with fine wire mesh d² so that water entering through the nipple is strained and freed from solid matters before it flows into the interior of the inner casing. I prefer to position the member D so that one of the panels d', between two windows, lies directly in front of the nipple; thus breaking the force of the inflowing water and air and dividing the same into streams which flow in opposite directions around the strainer. This arrangement brings the screens out of the path of the inrushing water and air and makes the strainer more effective.

The bottom wall of the casing has a flanged central opening G through which extends a tubular neck H carried by a dish-like member I which lies within the casing and rests upon the bottom.

K is a flexible diaphragm stretched across the top of the member I and having a central port therethrough. In manufacturing the valve, the diaphragm may be soldered across the top of the member I and the latter may then be slipped into the casing and be soldered or brazed in place. This construction has the advantage that the diaphragm may be mounted upon its support under good working conditions and the support may then be secured in place in the casing without danger of injuring the joint between it and the diaphragm. The port in the diaphragm may conveniently take the form of an axial opening l in a plug L which extends through the diaphragm at the center. The port in the diaphragm is controlled by a valve M carried by an expandible member supported within the upper part of the casing. The expandible member may conveniently take the form of a shallow inverted cup O having its mouth closed by a diaphragm P, the valve being connected to the diaphragm at the center. The expandible member may conveniently

be supported by means of a plug R which extends through the cap B at the center thereof and is adjustably held in place by screw-threads or the like; the expansible member having a stem S projecting upwardly from the same and connected to the plug R by means of a ball and socket joint T. It will be seen that by raising or lowering the plug the adjustment of the valve 5 relative to the port which it controls may be varied. By suspending the expansible member flexibly it is permitted to adjust itself so as to bring its axis into any desired angular position, therefore making it possible 10 for the valve to seat itself accurately even though either or both of the diaphragms should be out of true. The expansible member may be filled with any usual medium which will expand when heated so as to flex 15 the diaphragm P and cause it to bulge outwardly. In order to prevent injury to the diaphragm P, due to the creation of too high a vacuum within the expansible member, I prefer to arrange within the same a strut or 20 post U which will limit the inward movement of the diaphragm. This strut or post may also serve as a means of attachment for the valve, the valve having a screw-threaded portion m which extends through the dia- 25 phragm and is screwed into the post. 30 I prefer to make the member H large enough in diameter so as to permit the sleeve V of an ordinary union coupling between the valve and a water or air pipe to be secured 35 thereto.

W is a block which is soldered or brazed into the member H and has a bearing face w adapted to engage with a complementary bearing face v in the coupling. The outlet 40 from the casing is through a port or passage in the member W. I prefer to make the outlet passage in a tube or sleeve X which is screw-threaded or otherwise adjustably mounted in the member W so that 45 it may be raised and lowered, this member acting as a stop or abutment to limit the downward movement of the diaphragm K.

Assuming that the valve is connected in the air line of a heating system, the nipples 50 C being connected to a radiator which is cold: when steam is turned on, any air which there may be in the radiator passes ahead of the steam into the valve, depressing the diaphragm K and flowing through the port 55 into the air line. When steam reaches the valve, the expansible member becomes hot, its diaphragm bulges downwardly and the valve closes the port in the other diaphragm, forcing the latter diaphragm down until the 60 plug L engages with the member X. When steam is shut off, the expansible member cools, carrying the valve upwardly. The diaphragm K is so constructed that, when 65 free to do so, it assumes the position indicated in Fig. 2 and therefore, as the valve

cools, the lower diaphragm follows the receding valve and keeps the outlet port closed so that a high vacuum may be reached in the radiator after the steam has condensed. The valve may of course be used as a simple 70 air valve, there being no air line. In this case the operation of the valve will be the same as before, the air from the radiator simply escaping through the outlet port into the surrounding atmosphere. Where the 75 valve is connected in the return line of the heating system, carrying away the water of condensation, it operates in the manner previously described and, in addition, opens whenever the valve becomes filled with 80 water of condensation and permits the water to be discharged into the return line. It will be seen that the inflowing medium, either water or air, is thoroughly strained so that the valve and the port with which it co- 85 operates are kept free from grit and dirt. The windows do not extend clear to the bottom of the strainer so that the grit and dirt can pile up in the annular space surrounding the strainer without coming into contact 90 with the screens. In order to clean the valve it is only necessary to unscrew the cap and lift out the strainer, ready access being thus given to the interior of the device and the grit and dirt being readily removed. Simi- 95 larly, when it is desired to inspect the valve seat, it is only necessary to unscrew the cap, lifting the expansible member and its valve out of the casing and exposing the lower diaphragm.

While I have illustrated and described with particularity only a single form of my invention I do not desire to be limited to the specific details so illustrated and described; but intend covering all constructions and arrangements which fall within the terms employed in the definitions of my invention constituting the appended claims.

What I claim is:

1. In a valve for radiators, an outer casing having a detachable end, an open-ended inner casing extending between and held in place by the ends of the outer casing, an expansible member arranged within the inner casing and flexibly suspended from said detachable end, a diaphragm extending across the inner casing adjacent to the opposite end, said diaphragm having a port therethrough, a valve on said expansible member for controlling said port, said inner casing having windows therethrough, screens covering said windows, and the outer casing having an inlet port therein at a point outside of the inner casing and having also an outlet port at a point below the diaphragm.

2. In a valve for radiators, an outer casing having a detachable end, an open-ended inner casing extending between and engaging with said detachable end and the end opposite thereto so as to be held in place

thereby, a diaphragm extending across the inner casing, said inner casing having screened windows therein, the outer casing having an inlet at a point outside of the 5 inner casing and an outlet at a point below the diaphragm, said diaphragm having a port therethrough, and a valve device arranged within the inner casing above the

diaphragm for coöperating with the port in the diaphragm.

10

In testimony whereof, I sign this specification in the presence of two witnesses.

GEORGE D. HOFFMAN.
